SAMUEL MAKSIK, OF NEW YORK, N. Y., ASSIGNOR TO MICHEL MAKSIK & FELDMAN, INC., OF NEW YORK, N. Y., A CORPORATION OF NEW YORK

HAND-BAG

Application filed November 12, 1930. Serial No. 495,104.

This invention relates to a hand bag having a pocket or closure controlled by a slide fastener and has for its object to simplify the attachment of the fastener to the bag and to provide a neat and attractive closure which is easily operated without special stiffening means.

The invention is especially intended for hand bags made of soft, pliable material such as leather or cloth. When slide fasteners are used to close such bags, the soft fabric or leather tends to bunch and it is difficult to move the slider unless means are employed to stiffen the edges of the closure. This is true whether the fastener is used on the outer edges of the bag, or on the inside or outside pockets commonly provided in articles of this type.

I overcome this difficulty and at the same time simplify the construction of the bag by attaching the fastener stringers to the edges of the closure in inverted position along the outside of the bag, after which I fold the edges over and secure them to the inside 25 of the bag so that the stringers are held firmly in place and are stiffened by the double thickness of material at the folded edges of the closure.

In the preferred form of the invention, I also attach the lining of the bag to the edges of the closure by arranging it in inverted position coextensive with the fastener stringers, and then stitching or otherwise securing the lining and the stringers to the edges of the closure in one operation. The edges of the closure and the lining are then turned over inside the bag, and the edges cemented or otherwise secured in place, so that the cooperating fastener elements project outwardly while the rough attaching edges of the parts are concealed beneath the lining of the bag.

The invention will be described in connection with the accompanying drawings in which:

Fig. 1 is a perspective view of a hand bag in partly open position, showing one embodiment of the invention;

Fig. 2 is a detail view showing the method of securing a fastener stringer and the

lining to the cover in a single operation; and Fig. 3 is a transverse section through the bag when closed.

The drawings show a hand bag of the pouch type having the usual side walls or cover 1 connected by the gussets 2 which are grooved to fold inwardly when the bag is closed. The bag is made of leather, cloth or other suitable material, and is provided with handles 3 secured to buckles 4 which are anchored in any suitable manner in the sides of the bag. A layer of, canvas or other stiffening material 5 is glued or otherwise secured to the inside of the cover 1.

The slide fastener secured to the upper edges of the bag is of well known type consisting of tapes or stringers 6 having cooperating interlocking members 7 which are controlled by a slider 8. The slider is actuated by means of a pull member 9 having a tab 10 to facilitate opening and closing.

In attaching the fastener stringers to the bag, I first arrange the stringers 6 in inverted position along the upper edges 11 of the cover 1 so that the interlocking members 7 overlap the outside of the cover, as shown in Fig. 2. The cloth or other suitable lining 12 is arranged along the opposite sides of the stringers 6 so that it overlaps the outside of the cover 1. To facilitate this operation the lining 12 is preferably cut in two pieces which are separately attached to the respective edges of the bag in the manner described. The edge 11 of the cover, the fastener stringer 6 and the lining 12 are then secured together in one operation as by stitching 13, as shown in Fig. 2.

The edge 11 is then doubled over inside the bag, forming a flap, as shown in Fig. 3, and is secured in this position in any suitable manner, preferably by cementing it to the inside surface of the cover at 14. The lining 12 is also folded over inside the bag, as shown in Fig. 3, so that the stitches 13 and the attaching edges of the cover, stringer and lining are concealed from view, while the stringer occupies a substantially right angular medial position between the cover and lining. The cooperating rows of interlocking members 7 project outwardly from between the

the folded edges of the cover 1 and lining 12, but only so much of the stringers 6 is exposed as will insure a free track for the slider. This construction not only presents a neat and pleasing appearance, but also stiffens the fastener and makes it easy to move the slider in either direction with one hand.

5 The two halves of the lining 12 may be stitched together either before or after the edges 11 are cemented to the inside of the bag.

10 Likewise, the gussets 2 may be secured to the cover 1 either before or after the fastener and lining are attached. In the bag here shown the lining 12 is provided with a separate pocket or change purse 15 of the usual

15 type having a snap fastener 16.

In some cases I prefer first to attach the fastener stringers to the lining 12, with the stringer and lining in the position shown in Fig. 2, and then sew or otherwise fasten the

20 two to the cover as previously described.

Various changes may be made in the details of construction herein shown and described without departing from the scope

25 and spirit of the invention as defined in the appended claims.

The invention claimed is:

1. A closure for hand bags and the like comprising a cover made of soft pliable material having its edge folded inwardly to form a flap, a separable fastener stringer secured to said flap, a lining having its edge folded over and secured to said stringer, and means securing said flap to the inside of the cover with the stringer occupying a substantially right angular medial position between the folds of the cover and lining.

2. A closure for hand bags and the like comprising a cover and an inner lining having their upper edges folded over toward each other, a separable fastener stringer inserted between said folded edges and attached thereto with the attached portions concealed between the cover and lining, and means for securing said attached portions to the inside of the cover with the stringer occupying a substantially right angular medial position between the folds of the cover and lining.

30 Signed at New York in the county of New York and State of New York this 10th day of November, A. D. 1930.

SAMUEL MAKSIK.
